UNITED STATES PATENT OFFICE.

JOHN W. YATES, OF NEW YORK, N. Y.

FIREPROOF WINDOW.

1,340,312.

Specification of Letters Patent. Patented May 18, 1920.

Application filed May 4, 1918. Serial No. 232,438.

To all whom it may concern:

Be it known that I, JOHN W. YATES, a citizen of the United States, residing in the city of New York, borough of Manhattan, county and State of New York, have invented certain new and useful Improvements in Fireproof Windows, of which the following is a specification.

This invention pertains to fire proof windows, and relates, more particularly, to improvements in windows of the type wherein the frame and sash are constructed from rolled steel, in contradistinction to structures built up from sheet metal, known as hollow sheet metal windows.

Speaking generally, the invention embodies several coöperating features among which may be mentioned window locking means associated with the top of the frame and coöperating with the top of the sash, additional locking means associated with the bottom of the sash and coöperating with the sill, improvements in the window pivots and stop and structural improvements in the window frame and sash.

More specifically, the locking mechanism, in its preferred form, is composed of a member, preferably a type of angle iron, which extends the full length of the sash, both at the top and bottom thereof, which serves to not only lock the window with absolute security, but permits of the employment of a packing between the sash and the frame, and, also, between the locking plates and their associated parts, whereby the window is also rendered practically air, water, dust or noise proof.

The improvements in the pivots and gravity stop render them particularly efficient in rolled steel windows, and the structural changes in the frame and sash consist in the employment of shapes of special construction, which force the air entering between the sash and the frame to follow such a tortuous path as to practically prevent any perceptible drafts.

Features of the invention, other than those adverted to, will appear from the hereinafter detailed description, taken in conjunction with the accompanying drawings and appended claims.

In the accompanying drawings I have illustrated the preferred practical embodiment of the invention, though this specific

form is typical and not exclusive of the different forms in which the invention may be given expression.

Referring to the drawings, Figure 1 is a front elevation of the structure, showing the sash in closed position;

Fig. 2 is a sectional elevation taken on line 2-2 of Fig. 1;

Fig. 3 is a section showing the structure of the sash and frame above the pivots, taken on line 3-3 of Fig. 1;

Fig. 3^a is an enlarged detail of a portion of Fig. 3;

Fig. 4 is a front elevation, corresponding to Fig. 1, except that the sash is shown in open position;

Fig. 5 is a section, showing the structure of the sash and frame below the pivots, taken on line 5-5 of Fig. 1;

Fig. 5^a is an enlarged detail of the construction shown in Fig. 5;

Fig. 6 is a sectional elevation taken on line 6-6 of Fig. 4, showing the sash in open position;

Fig. 7 is a section taken on line 7-7 of Fig. 4;

Fig. 8 is a section on line 8-8 of Fig. 1 showing an enlarged detail of the top locking mechanism and its associated parts; and

Fig. 9 is a section on the line 9-9 of Fig. 1 showing an enlarged detail of the bottom locking mechanism and its associated parts.

Referring to the drawings, the building structure, in which the window is installed, is designated 1, the frame, in its entirety, 2, and the sash, in its entirety, 3,

The frame embodies the sill 4, formed of the two angle irons 4' and 4², secured together by riveting or welding, top member 5, also of angle iron, and the side members hereinafter described. In order to permit of the sash swinging inwardly from the top and outwardly from the bottom, both the side members of the frame and the sash are constructed differently, in cross sections, below the window pivots than above the same.

The cross sectional structure of said side members above the pivots is clearly shown in Figs. 3 and 3^a. Referring to the construction of the side members of the frame at this part of the window, they embody a T-iron 6, on the inner side of which is secured, by welding or otherwise, a Z-iron 7, relatively positioned as shown in

Fig. 3, whereby a channel or groove 8 is formed on the inner side of the frame. The sash at the part of the window described embodies an angle iron 9 to which is secured a U-shaped member 10, the legs of which are of unequal length, as shown, with the short leg 11, seating in channel 8 of the frame. Moreover, intermediate the long and short legs of the U-member, there is formed a channel 12, within which one leg of angle iron 9 is seated. The construction specified results, further, in the formation of a pocket or chamber 13 between the sash and the frame, so that, as plainly appears, air endeavoring to pass into or out of the building, when the window is closed, meets with several baffles which effectually preclude any possible draft.

In order to make the joint between the sash and the frame still tighter than is feasible even with the baffled construction described, felt or other suitable packing 14 is employed to line channel 12, thereby making the joint not only additionally air tight, but, also, dust, water and noise proof.

Referring now to the construction of the frame and sash below the window frame, as shown in Figs. 5 and 5^a, the side members of the frame embody a T-iron 15, on the inner side of which is secured what is, substantially in effect, a double Z-iron 16, or, more precisely, a Z-iron with a U-iron attached thereto, thereby forming the grooves or channels 17 and 18. The sides of the sash, at the parts under consideration, embody an angle iron 19, the forwardly projecting side of which 20, seats in the channel 18 to form a tight joint. Channel 18 is preferably lined with felt or other packing 21.

Referring now to the locking mechanism, and particularly to the top lock, this embodies, in its preferred form, a plate 22, of substantially the same length as the width of the sash, said plate being pivotally mounted, at its rear edge, through the pivot pins 23, at its ends, to the forwardly projecting legs on T-irons 6 of the frame. The front part of the locking plate 22 is hook shaped, in cross section, as shown at 24, so that, when in locked position, the hook portion extends downwardly so as to project over and embrace the upwardly extending member 25 of the angle iron 26, this latter iron forming the top cross piece of the sash. The rear face of member 26 is preferably lined with felt 27, as is, also, the inner face of the hook shaped portion 24 of the locking member, see 28, thereby forming especially tight joints between the sash and the frame and between the lock and the sash.

Locking plate or member 22 is provided, near its center, with a forwardly projecting nose piece 29, which co-operates with a pivoted, weighted latch or catch 30, pivoted at 31, to a plate or projection 32 on the sash,

whereby the lock may be released and the sash manually opened in the manner herein-after described.

Referring now to the bottom lock, see Figs. 1, 4, 7 and 9, this embodies a locking plate 33, of substantially the same form as the top locking plate 22, said plate 33 being provided at either end with a pintle 34, see Figs. 1 and 4, loosely mounted for pivotal movement in the side members 19 of the sash, whereby the sash may be tilted into and out of its locking position with respect to the sill, when the sash is opened and closed, respectively. The inner face of locking plate or member 33 is lined with felt 35, and a similar lining of felt 36 is applied to the inner face of the upstanding member 37 of the sill, thereby securing air-tight, noiseless junctures between the sash and the sill and between the locking plate and the sill. 85

The modes of operation of the top and bottom locking plates are substantially the same, both closing by gravity, but, as has been noted, the top locking plate is pivoted to the frame whereas the bottom locking plate is pivoted to the sash.

Projecting forwardly of the lower locking plate 33 is a nose piece 38, to which one end of the chain 39, is secured, said chain thence extending upwardly and being threaded loosely through a loop 40, connected with weighted latch piece 30, whence it extends, and is secured to a hook or catch 41 on the sill, whereby the sash is retained in open position, see Figs. 4, 6, and 7. The chain 39 is provided with the customary fusible link 42, whereby the chain is disrupted in the event of fire, and the sash automatically closed by gravity.

Referring now to the window pivot, on either side of the window, these embody an angle shaped attaching plate 43 secured to the sash and to each of which plates is affixed a pivot or trunnion 44. These pivots have bearings in supports 45, secured to the outer faces of the side members of the frame. The sash is thus free to turn on these pivots.

Pivotedly mounted on one of the attaching plates 43, through the medium of pivot 46, is a weighted gravity latch 47, the lower end of which, when the sash is opened, engages a stop 48 on the trunnion support 45, thereby limiting the forward, downward movement of the sash. By tilting the latch out of engagement with the stop, however, the rotary movement of the window can be continued, and thereby practically reversed; *i. e.*, the outside of the window made accessible from the inside of the building for cleaning, etc.

The operation of the structure described will be readily understood, but it may be briefly described as follows. When the sash is in closed or locked position, the upper and lower locking plates occupy the positions 130

shown in Figs. 1 and 2, and in full lines, on an enlarged scale, in Figs. 8 and 9, with the gravity catches occupying the positions shown. When, however, it is desired to open 5 the sash, a pull on the free or lower end of chain 39, causes the sash to tilt inwardly, and, synchronously therewith, the end of chain 39, being affixed to nose piece 38 of the lower locking plate, tilts the latter up- 10 wardly, free from engagement with the sill 4, whereas the intermediate upper portion of the chain, through its loose or running engagement with the gravity latch 30, causes the latter to be thrown upwardly on its 15 pivots, whereupon it engages the nose piece 29 of upper locking plate 22, and tilts it upwardly out of engagement with the top member 26 of the sash. The positions of the upper and lower locking plates, as well 20 as those of the nose pieces and gravity catches associated therewith, when the sash is in open position, is clearly shown in dotted lines in Figs. 8 and 9, and in full lines in Figs. 4, 6 and 7. The sash may then be 25 swung inwardly till the gravity latches 47 engage their stops, whereupon the sash is locked in open position by securing the end of the chain to hook 41, affixed to the sill. In the event of fire, fusible link 42 is dis- 30 rupted whereupon the sash automatically swings into closed position.

In sashes 5 feet, or over, in width, the underwriters' specifications call for the provision of two locks at the top and bottom of 35 the window, respectively, but, as yet, no simple construction has been devised which comes within the said requirements. The structure of the present invention, however, is, manifestly, superior to that called for by 40 the underwriters, yet it is simple and practical in construction and entirely efficient for its intended purposes.

It will be understood that the structure described may be varied in details, such as 45 by the substitution of equivalents, and that parts of the invention may be availed of without necessarily using them all in conjunction, or employing them in the specific environment shown, all without departing 50 from the spirit or substance of the invention as hereinbefore described, the scope of which is as broadly novel as is commensurate with the appended claims.

Having thus fully described the invention, what I claim as new, and desire to secure by Letters Patent, is:

1. A fire proof window embodying a sash, a frame, a locking plate pivoted near the top of the frame and adapted, when the 60 window sash is in closed position to overhang the top of the sash, a pivoted weighted latch adapted to release the locking plate, means for actuating the latch, the release, the locking plate and a chain, containing 65 a fusible link, for maintaining the sash in

open position, but permitting it to automatically close in the event of fire owing to the heat disrupting the fusible link.

2. A fire proof window embodying a sash, a locking member positioned at the top of 70 the sash and having its ends pivotally mounted in the side members of the frame, a locking member positioned near the bottom of the sash and having its ends pivotally mounted in the side members of the 75 sash, in combination with means associated with the sash and frame, for holding the sash in open position for ventilating and other purposes, said means embodying a heat disruptible member, whereby, in the event 80 of fire, the window is automatically closed.

3. A fire proof window embodying a sash, a locking member in the form of an angle iron positioned at the top of the sash and having its ends pivotally mounted in the 85 side members of the frame, a locking member in the form of an angle iron positioned near the bottom of the sash and having its ends pivotally mounted in the side members 90 of the sash, in combination with means associated with the sash and frame, for holding the sash in open position for ventilating and other purposes, said means embodying a heat disruptible member, whereby, in the event 95 of fire, the window is automatically closed.

4. A fire proof window embodying a sash mounted for pivotal movement on a horizontal axis, a frame in which the sash is pivoted, a locking member pivoted on the frame and adapted, when the sash is closed, 100 to overlie substantially the entire width of the upper edge of the sash and lock the sash in closed position, and means for pivotally moving the locking member into a position to release the sash to allow of the opening 105 thereof.

5. A fire proof window embodying a sash mounted for pivotal movement on a horizontal axis, a frame in which the sash is pivoted, a locking plate pivoted on the frame 110 and adapted, when the sash is closed, to overlie substantially the entire width of the upper edge of the sash and lock the sash in closed position, and a manually operable member for releasing the locking plate to 115 allow of pivotal movement of the sash to open position, said member being weighted to normally gravitate into a position to leave the locking member in locked position.

6. A fire proof window embodying a 120 frame, a sash mounted for pivotal movement in said frame on a horizontal axis, a pivoted locking member mounted on the frame and adapted to automatically gravitate into a position to overlie the upper edge of the 125 sash and lock the sash in closed position, said locking member being of a width substantially co-extensive with the width of the sash, whereby it serves the simultaneous purpose of precluding drafts from entering 130

- between the top of the sash and the frame, and means for releasing the locking member to allow of pivotal movement of the sash to open position.
5. 7. A fire proof window embodying a frame, a sash mounted for pivotal movement on a horizontal axis on said frame, a pivotal locking member of substantially the same width as the sash mounted on the frame and 10 adapted to normally overlie the top of the sash to lock said sash in closed position, a pivoted locking member mounted near the bottom of the sash, said second locking member being substantially equal in length to the width of the sash and adapted to normally overlie the adjacent portion of the frame to further lock the sash in closed 30 position, manually operable means associated with the upper and lower locking members to simultaneously release the sash at both its top and bottom to allow of its pivotal movement to open position, means for maintaining the sash in open position, and means, including a fusible connection, for automatically releasing the sash when a predetermined temperature is reached to allow of the closing of the sash and the automatic 40 locking thereof in closed position.
- 15 8. A fire proof window embodying a frame, a sash mounted for pivotal movement on a horizontal axis on said frame, 20 25

a pivotal locking member of substantially the same width as the sash mounted on the frame and adapted to normally overlie the top of the sash to lock said sash in closed position, a pivoted locking member mounted near the bottom of the sash, said second locking member being substantially equal in length to the width of the sash and adapted to normally overlie the adjacent portion of the frame to further lock the sash in closed 35 position, manually operable means associated with the upper and lower locking members to simultaneously release the sash at both its top and bottom to allow of its pivotal movement to open position, means for maintaining the sash in open position, and means, including a fusible connection, for automatically releasing the sash when a predetermined temperature is reached to allow of the closing of the sash and the automatic 45 locking thereof in closed position.

In testimony whereof I have signed my name to this specification.

JOHN W. YATES.
